CLAIM

The ornamental design for a combined lamp and lamp base as shown and described.

DESCRIPTION

FIG. 1 is a front, right and top perspective view of the lamp portion of the combined lamp and lamp base, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of the combined lamp and lamp base.

FIG. 10 is a rear, right and bottom perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan elevation view thereof.

FIG. 16 is a bottom plan elevation view thereof.

FIG. 17 is a front, right and top perspective view of the combined lamp and lamp base of FIG. 9, in an alternate state.

FIG. 18 is a rear, left and bottom perspective view thereof.

FIG. 19 is a front elevation view thereof.

FIG. 20 is a rear elevation view thereof.

FIG. 21 is a left side elevation view thereof.

FIG. 22 is a right side elevation view thereof.

FIG. 23 is a top plan elevation view thereof; and,

FIG. 24 is a bottom plan elevation view thereof.

(Continued)

The broken lines depict portions of the combined lamp and lamp base that form no part of the claimed design.
